ATTORNEYS

UNITED STATES PATENT OFFICE.

HENRY KRUESHLD, OF NEWARK, NEW JERSEY.

PIPE REAMER.

Application filed September 23, 1924. Serial No. 739,377.

To all whom it may concern:

Be it known that I, HENRY KRUESHLD, a citizen of the United States, and a resident of Newark, in the county of Essex and State 5 of New Jersey, have invented a new and Improved Pipe Reamer, of which the following is a full, clear, and exact description.

This invention relates to a new and improved pipe reamer, especially adapted for 10 tobacco pipes.

An object of the invention is to provide a simple, compact, durable and strong pipe reamer which is adapted to be collapsed when not in use so that it can be readily sus- 15 pended on a key ring.

Another object concerns the provision of a pipe reamer which can be suspended on a key ring and at the same time be quickly and easily extended into operative position 20 for the purpose of reaming out a pipe, preferably a tobacco pipe, although other tubular articles can be reamed therewith.

A further object concerns the provision of means whereby the device can be made of 25 simple, inexpensive material, preferably sheet metal, and so as to occupy a very small space when not in use.

The invention is illustrated in the drawings, of which—

30 Figure 1 is a section through the bowl of a pipe showing the reamer in position;

Fig. 2 is a perspective view showing the reamer in its collapsed closed position;

Fig. 3 is a perspective view of the reamer 35 showing it in open or operative position;

Fig. 4 is a section taken on the line 4—4 of Fig. 2; and

Fig. 5 is a section taken on the line 5—5 of Fig. 3.

40 The form of the invention shown in the drawings is a preferred form, although it is understood that modifications in the construction and arrangement of the parts and in the character of the materials used may 45 be adopted without departing from the spirit of the invention as set forth in the appended claims.

In its general aspect the invention com- 50 prises two metal plates the edges of which are formed to conform to the profile of the bowl of a pipe, preferably a tobacco pipe. These edges are curved and sharpened and act as cutting edges. These plates are slotted and are so disposed with respect to each other as to be movable one with respect to the other but are not ordinarily com-

pletely disengageable. Their normal position when in operation is at right angles to each other, whereas when not in operation they are adapted to be swung relative to each other to lie flat against each other. A simple little latch is provided on one of the plates to be moved into position to grip both of the plates and hold them in their closed position. These plates are provided with 60 slots in order to permit their being swung flat against each other without disengagement and are necessarily provided with portions offset with respect to each other so that the pivotal swinging movement can take 65 place.

The particular form of the invention which constitutes the preferred embodiment thereof is shown in the drawings and is adapted to be used to ream out the bowl 1^a 70 of a pipe, as shown in Fig. 1. The reamer preferably constitutes the two plates A and B. These plates are formed of wing portions 1, 2, 3 and 4, each plate being provided with two wing portions. One wing portion 80 of a plate is offset with respect to the other wing portion, thereby providing a sort of shoulder 5, as shown in Fig. 4. Each plate is provided with this sort of shoulder. The plate A is provided with a slot 6. The 85 plate B is provided with two slots 7 and 8, the slot 7 being closed at both ends but the slot 8 being open at the bottom or lower end of the plate B. In the manufacture of the device the plate B is cut or slit between the 90 two slots therein and separated far enough to permit the plate A to be slipped into position. Thereafter this slit is sealed by either soldering or welding so as to bind the 95 separated edges and confine the plate A into permanent pivotal engagement with the plate B.

A latch member 9 is mounted on one of the plates such as B and adapted when 100 swung down to engage with one of the wings of the plate A when said plate is swung into a position flat against plate B. The slot 7 extends well up into the plate B and its upper end lies above a shoulder or enlarged portion 10 formed thereon so that the plate A as it is swung into operative position is moved up into the upper end of slot 7 so 105 that its upper face lies against this portion of the plate B. This provides a certain amount of rigidity to the plate. Normally, to place the parts in their closed position the plate A is allowed to drop a bit until its 110

upper edge is below the shoulder 10, and then is swung around flat against the plate B and locked. In this locked position it will be seen that the lower edge 11 of the plate A lies below the lower edge of the plate B but that normally when they are in their operative relation, as shown in Fig. 3, their lower edges are at the same level. The upper portion of the plate B may be provided with a key head or plate 12 adapting the device to be mounted or suspended from a key ring if desired.

This device, therefore is adapted for ready suspension on a key ring and can be quickly and easily placed in operative condition for use in reaming the bowl of a pipe. It is to be clearly understood that this reaming device can be used for other things besides tobacco pipes and it is not my intention to limit it to this use.

What I claim is:—

1. A pipe reamer, which comprises a pair of pivotally movable plates adapted in one position to be disposed at an angle to each other for reaming purposes and to be disposed flat against each other when not in use.

2. A pipe reamer, which comprises a pair of pivotally movable plates adapted in one position to be disposed at an angle to each other for reaming purposes and to be disposed flat against each other when not in use, and means on one of said plates to en-

gage with the other to lock the plates in their closed position.

3. A pipe reamer, which comprises a pair of pivotally engageable collapsible plates adapted to be disposed at an angle to each other when in use and collapsed against each other when not in use.

4. A pipe reamer, which comprises a pair of plates having slots therein, the slotted portions on one plate adapted to pass through the slots in the other, each plate being offset in line with the slots to permit one plate to be swung flat against the other.

5. A pipe reamer which comprises a plate having slots therein, shoulders at the upper end of this plate on opposite sides thereof adjacent the upper end of one of said slots, a second plate having a slot embracing the unslotted portion of the first-mentioned plate, said plates having offset portions in line with the slots to permit them to be swung flat against each other, said second plate adapted to be swung at an angle to the first plate and moved into engagement with the shoulders whereby it can be maintained substantially in this angular position during use, said second plate adapted to be dropped down into the slots of the other plate prior to being swung flat thereagainst.

HENRY KRUESHELD.
